UNITED STATES PATENT OFFICE

AMERICUS D. BASINGER, OF PLYMOUTH, NORTH CAROLINA, ASSIGNOR OF ONE-HALF
TO ROBERT P. WALKER, OF PLYMOUTH, NORTH CAROLINA

VENEER KNIFE

Application filed September 1, 1928. Serial No. 303,441.

This invention relates to knives for use upon veneer cutting machines and its object is to reduce the cost of the knives, prolong the effective life of the same and lessen the cost of maintenance. These objects are attained in such a device as is illustrated in the accompanying drawing, and the invention resides in certain novel features which will be particularly defined in the appended claims.

10 In the drawing:

- Fig. 1 is a plan view of a knife structure embodying the present invention;
- Fig. 2 is a similar view with the top plate or clamping bar removed;
- 15 Fig. 3 is a section on the line 3—3 of Fig. 2;
- Fig. 4 is a section on the line 4—4 of Fig. 1;
- Fig. 5 is a detail perspective view showing the knife-adjusting elements in proper relation but separated, and
- 20 Fig. 6 is a plan view of a filler bar.

Veneer knives, as now generally constructed, consist of a flat bar of metal held between two frame bars or clamping plates and provided in their inner edge portions with a plurality of notches to accommodate the fastening devices whereby the clamping bars are held together and to the knife. As the knife is sharpened, the cutting edge approaches the ends of these notches and eventually the cutting edge will wear through so that the ends of the notches break away and an uneven cut of the log is the result. When this condition arises, the remaining portion of the knife is waste material. Moreover, with such construction, it is necessary to entirely separate the knife-holding bars in order to permit the removal or reinsertion of the knife when regrinding is necessary which means a loss of time and, moreover, requires the expenditure of considerable labor in effecting a uniform adjustment of the knife when it is in place between the bars. The present invention provides means whereby the present waste is avoided and the knife may be easily adjusted while in place between the clamping bars and will be uniformly adjusted through its entire length.

In carrying out the invention, there is provided a lower clamping or knife-holding bar 1 having a rib 2 extending along its back

edge and constituting a guiding abutment, as will presently more fully appear. Between the edges of this bar, square lugs 3 are formed thereon in equally spaced relation and threaded openings are formed through said lugs and the bar, as will be understood, the sides of the lugs being parallel with the edges of the bar. The upper clamping bar 4 is provided adjacent its rear edge with threaded openings receiving set bolts 5 which are 55 adapted to impinge against the upper surface of the rib 2. In the upper surface of the bar 4, recesses 6 are formed at intervals corresponding to the spacing of the lugs 3 and in the under side of the upper bar 4 are formed 60 cavities, indicated at 7, to accommodate the upper ends of the several lugs 3. Securing bolts 8 are inserted through the upper bar to engage the threaded openings in the lugs 3 and the lower bar, the heads 9 of these bolts 65 being received within the recesses 6, as shown. These described fastening devices secure the bars 1 and 4 together in such manner that relative movement of either bar is prevented 70 while at the same time a space is defined between the bars to receive the knife blade 10 and adjusting devices which are about to be described, the set bolts 5 providing for a limited rocking of the upper bar whereby its 75 forward edge will be caused to bear strongly 80 upon the blade adjacent the cutting edge thereof. It may be noted upon reference to Fig. 3 that the lower clamping bar 1 is extended very close to the extreme cutting edge 85 of the knife so that the knife is very firmly 90 supported and will effectually maintain its engagement with the log during the cutting operation. According to my invention, the knife blade has an uninterrupted straight 95 back edge, as shown at 11. Resting slidably 100 upon the clamping bar 1 between the several lugs 3 are followers 12 of the same thickness as the knife blade and having straight ends 13 presented to and bearing against the back edge of the blade, the side edges of these followers being straight and parallel so as to fit closely but slidably between adjacent lugs, as clearly shown in Fig. 2, while the back ends of the followers are disposed diagonally, 105 as shown at 14. Resting slidably upon the

bar 1 between the series of lugs 3 and the rib 2 is an adjusting bar or slide 15 having its back edge 16 straight to abut the rib 2, as shown in Fig. 2, while its forward edge is formed into spaced extensions 17 alternating with the followers 12 and each presenting a diagonal edge 18, adapted to engage the diagonal edge 14 of a follower, and a straight front edge 19 adapted to engage and ride upon the back edge of a lug 3. Near one end of the slide or adjusting bar 15, an internally threaded lug or boss 20 is formed thereon and the clamping bar 4 is provided with a longitudinal recess or slot 21 accommodating said lug or boss. A bearing plate 22 is provided to close the outer end of said slot and in said plate is swiveled a screw or adjusting bolt 23 which has its inner end engaged in the bore of the boss 20 and its outer end constructed to be engaged by a turning tool. It will be readily seen that rotation of the screw will cause the boss 20 to ride along the same and correspondingly shift the slide 15. When the knife is new, the slide is placed at the extreme limit of its movement toward the right in Fig. 2, and the several followers 12 will then have their tapered ends engaged between the several teeth of the slide with their front straight end edges bearing against the back edge of the blade, as shown in Fig. 2. When the knife is to be adjusted to compensate for wear, the bolts 5 and 9 are loosened just enough to release the clamping action of the bars 1 and 4 upon the blade, the slide and the followers, after which the screw 23 is rotated so as to effect movement of the slide to the left. As the slide thus moves to the left, the engaging diagonal edges on the slide and the several followers will cause the followers to move forwardly and this movement will be transmitted directly to the knife blade so that the latter will be set forwardly to the desired degree. The bolts 5 and 9 are then turned home and the parts will operate as before. When the knife bar has been worn and adjusted to such an extent that the followers will no longer be in engagement with the slide, a filler bar 25, shown in Fig. 6, is employed. This bar is a rectangular bar of the same thickness as the blade and the followers and of a length equal to the length of the blade. By merely inserting this filler bar between the back edge of the blade and the front edges of the several followers, the described adjustments may be repeated and the blade used until there is no longer sufficient material to permit the clamping bars 1 and 4 to secure the same.

From the foregoing description, taken in connection with the accompanying drawing, it will be seen that I have provided an exceedingly simple mechanism which will permit the use of a knife blade until it has been entirely consumed and which will facilitate the adjustment of the blade to take up wear

and in which the entire length of the blade may be simultaneously adjusted. The knife is secured in position upon the veneer machine in the same manner as the knives and knife holders now in use.

Having thus described the invention, I

1. The combination of a lower clamping bar having a series of equi-distant straight sided lugs on its upper face between its front and rear edges and a straight rib on said face along its rear edge, an upper clamping bar provided on its lower face with recesses to fit over said lugs and said rib and be thereby held against relative turning movement, a knife fitting between the forward edges of the bars, followers fitted between the bars and slidably engaged between and guided by said lugs and bearing against the back edge of the knife, an adjusting bar slidably resting on the lower clamping bar between the rib and lugs thereon and engaging the rib and the followers to shift the followers laterally for setting the blade, and means for securing the clamping bars together whereby to hold the blade, the followers and the adjusting bar in operative relation.

2. The combination of upper and lower clamping bars, a knife blade fitted between the front portions of the bars, followers slidably mounted between the bars and provided with diagonally disposed back edges and having their front edges extending parallel with the front edges of the bars and abutting the back edge of the blade, means for guiding said followers in paths at a right angle to the length of the blade, an adjusting bar slidably fitted between the clamping bars longitudinally thereof at the rear of the followers and having diagonally disposed edge portions engaging the diagonal edges of the followers, and having its back edge slidably engaged with the lower clamping bar, interengaging means on the clamping bars to prevent relative turning movement thereof, said means also constituting guides for the followers, means cooperating with the last-mentioned means to secure the clamping bars together, and means for shifting said adjusting bar endwise of the clamping bars.

3. The combination of a lower clamping bar having a longitudinal series of lugs on its upper face between its front and rear edges, and a rib on its upper face along its rear edge, said lugs having edge portions parallel with the edges of the bar, an upper clamping bar provided on its lower face with recesses to engage said lugs and rib whereby to be held against relative turning movement, means for securing the clamping bars together, a blade disposed between the front portions of the clamping bars, a slide resting on the lower clamping bar between and bearing against the rib and the lugs thereon and having diagonal edge portions alternating

with the lug-engaging edge portions, means mounted at one end of the lower clamping bar to adjust the slide thereon longitudinally, and followers slidably resting on the lower clamping bar between and guided by the lugs and having their front edges arranged to exert pressure on the back edge of the blade and having their back edges disposed diagonally and engaging the diagonal edge portions of the slide.

10 In testimony whereof I affix my signature.
